ABSTRACT OF THE DISCLOSURE

A coded photographic record card for use with data storage and retrieval devices is made by cropping a length of film from a conventional strip of the same including sprocket openings located along one or both edges of the strip. One or both longitudinal marginal edge portions of such length of film material are thereafter removed by severing the webs located between the sprocket openings along lines located either near the in-board or near the outboard ends of each web so as to produce either the presence or absence of a coding tab at each web location depending on the location of the line along which each web is severed.

This invention relates to data storage and retrieval devices and more particularly to a system for coding cards fabricated from standard perforated photographic film.

Micro-film is widely used for the storing of images of signed or original documents, photographs, fingerprints, drawings, and any such material of the class which does not translate efficiently into binary language for storage in a memory. One form for storing such micro-film records according to the present art is to cut the film into short lengths each of which carries one or several images of such material and mount each said length in a data card. The cards may then be stored in a file or stack in such manner that individual cards can be retrieved by sequential or simultaneous search.

To facilitate the retrieval of any particular card from a stack of cards, each card comprising the stack is usually coded with a unique coding. Such coding may comprise an array of punched holes of the form used in well known sequential search devices, or same may comprise one or more rows of tabs any of which can be removed to achieve unique coding, of the form used in known simultaneous search devices. Accordingly, it is an object of this invention to provide a simplified data storage device constructed from standard perforated photographic film.

A card according to this invention comprises a length of perforated photographic strip film, defined herein as any form of standard photographic film perforated with sprocket holes, from which the edges adjacent to the perforations have been removed by slitting longitudinally along a line adjacent to the outer limit of the maximum width of the perforations in such manner that the web of film material normally disposed between the perforations or sprocket holes becomes coding tabs. The identification coding of a card of such form is performed by removing certain combinations of such tabs in accordance with a prearranged order.

Alternatively, cards according to this invention may be coded simultaneously with the removal of the outer edges of the perforated film by longitudinally severing the inner or the outer limit of said web of material disposed between each perforation in accordance with the coding array desired. In fabricating cards according to the invention the cropping of the continuous film to the length desired for the card need not be performed until after

2

slitting, coding, development and drying of the film is complete.

In order to prevent photographic film cards of the invention from excessive curling due to changes in temperature and humidity, there may be provided a stiffening frame connected to the card in such manner that the outer edges of said frame approximately coincide with the inner edges of the sprocket holes. To minimize the cost of construction of micro-film cards according to the invention, the stiffening frame may comprise two opposing right angle members. The stiffening frame may furthermore be formed with one or more opposite pairs of outwardly extending teeth to reinforce the corner or other teeth of the card against wear and possible fold-over.

It is therefore another object of this invention to provide a data storage device constructed from perforated photographic film.

It is another object of this invention to provide a means for coding perforated photographic film utilizing the existing sprocket holes.

Other objectives of the invention will become apparent from the accompanying specification read with the drawing, in which:

FIG. 1 is a view of a micro-film card according to the invention formed from standard double-perforated 35 mm. photographic film,

FIG. 2 shows an enlarged plan view of one edge of a perforated photographic film including three complete sprocket holes,

FIG. 3 shows a micro-film card according to the invention formed from double-perforated 35 mm. photographic film with means for coding one side of the card simultaneously with the removal of same edge of the original film,

FIG. 4 shows a single coding means of the device of FIG. 3,

FIGS. 5 and 6 illustrate a card having different forms of reinforcing frames, and

FIG. 7 shows a portion of a card having a one piece frame formed with a plurality of reinforcing tabs which coincide with the tabs in such card.

Referring now to the drawing and in particular to FIGS. 1 and 2, a micro-film card 11 comprises a length of standard 35 mm. photographic double perforated film 12, the ends 13 and 14 of the card 11 are cropped so that the card is equal to eleven sprocket pitches in length. The central part of the card, as is conventional, serves as the data receiving area on which data is photographically recorded. The opposite sides 15 of the film 12 are longitudinally slit along the outer limit of the full depth d of perforations 16 in such a manner that the limit comprises the edges 17 of card 11.

The webs of material disposed between adjacent perforations 16 become coding tabs 18 which may be subsequently removed in such manner as to comprise a unique identification coding for search and retrieval purposes in accordance with a well known technique which is not a part of this invention. Referring now to FIGS. 3 and 4 a strip of single perforated photographic film 20 has emerged from a micro-filming camera 21 and is at rest at a coding station where it comes into alignment with a plurality of shear cutters 22. At the outer end of the coding station a lateral cropper 23 is disposed which crops continuous film 20 into correct lengths. Each cutter 22 aligns with the web of material between adjacent sprocket holes 24 and there are as many shear cutters as there are webs of material in the length of card to be generated.

The shear cutters 22 are laterally slidable throughout a stroke substantially equal to the width b of the web (as seen in FIG. 2) and each is provided with a vertical

extension 25 enabling manual movement of same to its inner or its outer limit of lateral movement. The lower wing of each cutter 28 is supported and guided on a base 27 and the upper wing 28 of each said cutter can be depressed to perform the shearing action. A bar 29 extending the length of all cutters is supported on suitable arms, the ends of which are pivoted to the base in such manner as to enable simultaneous operation of all shear cutters.

In operation, following the emergence of photographic film 20 from camera 21 each shear cutter 28 is moved inwardly or outwardly by manual movement of its extension 25 in accordance with the coding desired, and the bar 29 is depressed thereby simultaneously cutting the webs and removing the edge material off the film 20 in such a manner that the desired coding tabs are generated by the said edge removing procedure. The film 20 is then fed under shears 22 through the correct number of pitches.

It will be understood that in the above embodiment the setting and operation of the shear cutters 22 and cropper 23 may readily be adapted to automatic and remotely controlled mechanisms of well known construction which are beyond the scope of this invention.

Referring now to FIGS. 5 and 6, coded card 30 is provided with a stiffening frame 31 which is bondingly connected thereto by a permanent bond of well known formulation (not shown). Stiffening frame 31 is blanked from a thin ribbon of metal the central window 32 of which is waste. To improve the economy of stiffened cards according to the invention, frame 31 may be replaced by the frame illustrated in FIG. 6 comprising two pieces 33 and 34.

In some cards according to the invention it may be desirable to stiffen all or some of the film coding tabs. The invention provides as shown in FIG. 7 that the stiffening frame 35 may be formed with a plurality of teeth 36 which substantially coincide with coding tabs 37 of the film card 38 and may be bondingly connected thereto in such manner as to stiffen tabs 37.

Although the invention has been described and illustrated in detail, it is to be clearly understood that the same is by way of illustration and example only and is not to be taken by way of limitation, the spirit and scope of this invention being limited only by the terms of the appended claims.

I claim:

1. The method of making a coded record card, which method comprises the steps of cutting a length of photographic film from a strip of such film having sprocket openings arranged in spaced succession along at least one longitudinal edge thereof and separated from one another by individual webs of the film material, and removing the marginal edge portion of said length of film along said one edge thereof by severing each web of said edge portion along a line spaced inwardly from said one edge by a distance depending on the coded representation to be established so that the portions of said webs thereafter remaining with the main body of said length of film constitute laterally outwardly extending code tabs setting up the desired coded representation.

2. The method of making a coded record card as defined in claim 1 further characterized by said step of removing the marginal edge portion of said length of film

being accomplished by severing each web of said edge portion along a line located either near the outboard end or near the inboard end of said web in accordance with the coded representation to be established so as to provide on the finished card either a full-length code tab or substantially no code tab at the location of each of said webs.

3. The method of making a coded record card as defined in claim 1 further characterized by attaching a stiffening frame to at least one side of said length of film in such a manner that said code tabs extend laterally outwardly from the periphery of said frame.

4. A coded record card for use in data storage and retrieval devices comprising a generally rectangular piece of photographic film having a central data receiving area on which data is photographically recorded, said record card also having along at least one edge thereof a number of code tabs extending laterally outwardly from the body of said card and spaced from one another longitudinally of said one edge which code tabs are made of the same material as the remainder of said piece of photographic film and are integral with the main body thereof.

5. A coded record card as defined in claim 4 further characterized by a plurality of code tabs located along a second edge of said card parallel to said one edge which latter code tabs extend laterally outwardly from said body of said piece of photographic film and are spaced from one another longitudinally along said second edge.

6. A coded record card as defined in claim 4 further characterized by a stiffening frame attached to said piece of photographic film, said stiffening frame having a central window within which said data receiving area of said piece of film is received and also having one outer edge extending along the inboard ends of said code tabs.

7. A coded record card as defined in claim 6 further characterized by said stiffening frame having a plurality of laterally outwardly extending teeth each of which overlies a portion of an associated one of said code tabs.

8. A coded record card as defined in claim 6 further characterized by said stiffening frame comprising two substantially identical parts each located adjacent an opposite face of said piece of film material.

9. A coded record card for use in data storage and retrieval devices and cut from a length of photographic film having sprocket openings arranged in spaced succession along at least one longitudinal edge thereof and separated from one another by individual webs of the film material, said record card comprising a piece of photographic film such as aforesaid having a main data receiving area and a plurality of laterally outwardly extending code tabs spaced from one another along one edge thereof, said code tabs consisting of selected ones of the webs originally forming a part of said piece of film.
